ELECTRIC MOTOR CONTROL SYSTEM

Ralph G. Lockett, Wauwatosa, Wis., assignor to
 Cutler-Hammer, Inc., Milwaukee, Wis., a corporation of Delaware

Application February 1, 1935, Serial No. 4,157

8 Claims. (Cl. 34—5)

This invention relates to improvements in electric motor control systems. Although not limited thereto, the invention is particularly applicable to control of the fan and cylinder driving motors of a clothes-drying tumbler or the like.

An object of the invention is to provide a novel system of control for a plurality of associated electric driving motors.

Another object is to provide a system of the character aforementioned wherein a single manual control instrumentality may be utilized to initiate joint operation of the motors.

Another object is to provide such a system wherein a single manual control instrumentality may be utilized to simultaneously interrupt the energizing circuits of both motors.

Another object is to provide a system of the aforementioned character embodying a relatively large motor and a relatively small motor, and wherein the starting resistance for the relatively large motor is utilized to additionally provide initial protection for the relatively small motor during starting.

Another and more specific object is to provide a simple form of starting control means for a relatively large fan operating motor, said means being utilized to insure protection to a relatively small cylinder driving motor having a reversing and accelerating control drum and resistance sections individual thereto.

Another object is to provide a system wherein the fan motor is utilized to drive the reversing and accelerating control drum associated with the cylinder motor.

Another object is to generally improve and simplify the control means for a plurality of associated driving motors to provide for accomplishment of the novel results aforementioned.

Other objects and advantages of the invention will hereinafter appear.

The accompanying drawing illustrates an embodiment of the invention which will now be described, it being understood that the embodiment illustrated is susceptible of modification without departing from the scope of the appended claims.

The drawing illustrates schematically and diagrammatically a system of control for the relatively large fan driving motor and for the relatively small cylinder driving motor of a clothes-drying tumbler of the character employed in laundering establishments.

Referring to the drawing, the numeral 5 designates the rotatable cylinder of a well known form of clothes-drying tumbler. Cylinder 5 is prefer-

ably provided with a plurality of compartments to which access may be had by means of a corresponding number of slideable or otherwise movable doors designated respectively by the numerals 6 and 7. In practice the cylinder 5 is mounted within and enclosed by a suitable housing or casing (not shown),—said casing being of known construction and having appurtenant parts to provide for initially supplying to the cylinder a flow of heated air and for thereafter supplying to 10 said cylinder a flow of air at normal or atmospheric temperature. The aforementioned casing is likewise preferably provided with a movable door or doors with which the respective compartment doors of the cylinder may be brought into 15 register to provide for depositing of clothes within or removal thereof from said compartments.

Cylinder 5 is adapted to be driven, through suitable speed-reducing gearing 8, by an electric motor M the armature of which is designated by 20 the numeral 9,—said motor being provided with a series field 10 and a shunt field 11. Motor M may be and preferably is of relatively small capacity, say 3 H. P. Cylinder 5 preferably has associated therewith a manually operable brake 25 12 to provide for final stopping of the cylinder with the compartment doors thereof in register with the aforementioned casing door. I further preferably provide a worm 13 which is movable at will into engagement with a gear 14 associated 30 with the cylinder,—said worm being provided with a crank handle 15 to provide for manual movement of the cylinder in either direction to bring the compartment doors thereof into the desired angular position, in the event that the 35 same are inaccurately positioned upon stopping of the cylinder by application of brake 12.

Motor M is provided with means, including a drum 16 and associated resistance sections 17, 18 and 19, to normally provide for periodic reversal 40 and step-by-step acceleration of said motor, after completion of the circuit for the latter. Drum 16 is rotatable unidirectionally, as indicated by the arrow,—the same being driven, through the medium of speed-reducing gearing 45 20, by a motor M¹ the armature of which is designated by the numeral 21.

Motor M¹ is preferably of relatively large capacity, say 15 H. P., to provide for driving of the fan shown diagrammatically at 22. Motor 50 M¹ is provided with a series field 23 and a shunt field 24, and said motor is adapted to be connected across a suitable source of energy supply, represented by lines L¹, L², upon closure of the normally open contacts 25^a of an electromag- 55

netically operable switch 25, the operating winding of which is designated by the numeral 25^b—assuming prior closure of a knife switch of usual form, as represented by the contacts 26 and 27.

- 5 Energization and de-energization of the winding 25^b may be effected at will through the medium of a pair of push-button switches 28 and 29,—switch 28 being of the normally open type, and switch 29 being of the normally closed type.
- 10 Thus upon closure of switch 28 a circuit is completed from line L¹ by conductor 30 through said winding 25^b and through the contacts of switches 29 and 28 to line L². Switch 25 is provided with normally open auxiliary contacts 25^c adapted
- 15 upon closure thereof to provide a maintaining circuit for winding 25^b in shunt to the push-button switch 28, as will be obvious, wherefore only momentary closure of the latter is necessary. Closure of switch 25 in the manner just described
- 20 provides for completion of a circuit for unidirectional operation of motor M¹, said circuit extending from line L¹ through the series field 23 and armature 21, thence through a starting resistance 31 and contacts 25^a to line L². The circuit for
- 25 the shunt field 24 extends from line L¹ through said shunt field and contacts 25^a to line L², as will be apparent.

Drum 16 is provided with segments 32 to 45, inclusive, and with contacts 46 to 54, inclusive, for cooperation therewith. In the event that drum 16 is so positioned upon closure of the contacts 25^a of switch 25 as to provide for engagement of either of the segments 32 or 39 with contact 46 it will be apparent that all of the resistance sections 17, 18 and 19 will be excluded from the armature circuit of motor M. Accordingly, to insure proper protection for motor M during starting thereof I provide for initial inclusion of resistance 31 in circuit in series with field 10 and armature 9 of said motor. Under these conditions a circuit is provided for motor M which may be traced from line L¹ through series field 10 to contact 54, segments 38 and 37 to contact 53, by conductor 55 through armature 9, conductor 56 to contact 50, thence through segments 35 and 32 to contact 46, by conductors 57 and 58 through resistance 31, and through the contacts 25^a to line L². The circuit for shunt field 11 extends from line L¹ through said field 11 and contacts 25^a to line L².

I provide means for automatically excluding resistance 31 to effect acceleration of motor M¹. Said means comprises an electromagnetically operable switch 59 having normally open contacts 59^a and an operating winding 59^b. As shown the winding 59^b is connected across the terminals of armature 21, and said winding is calibrated in a well known manner to respond and effect closure of the contacts 59^a upon attainment of predetermined current conditions in the circuit of motor M¹, thereby short-circuiting resistance of resistance 31 to effect full speed operation of motor M¹. The aforescribed automatic operation will likewise effect exclusion of resistance 31 from the circuit of motor M, but in the meantime drum 16 will have been rotated by motor M¹ to such an extent as to provide for proper control of the acceleration of motor M through the medium of resistance sections 17, 18 and 19.

As will be apparent to those skilled in the art, if the drum 16 is in neutral or circuit interrupting position at the time of closure of contacts 25^a, the circuit for motor M will only be completed upon engagement of segments 35 to 38

(or 42 to 45) with their cooperating contacts, thus initially including in the circuit of said motor both the resistance sections 17, 18 and 19 and resistance 31,—which arrangement is not objectionable, because the motor M will under these conditions be able to start. As soon as motor M¹ has been brought up to full speed by exclusion of resistance 31, motor M will be subject to normal reversing and acceleration control by drum 16, the operation of which is believed to be obvious.

As will be apparent from the foregoing description the operation of both of the motors M¹ and M is initiated simultaneously or substantially simultaneously by momentarily depressing the push-button switch 28. In a like manner the circuits of both motors M¹ and M may be interrupted by momentarily depressing push-button switch 29, whereby the winding 25^b is de-energized with consequent opening of the contacts 25^a.

Both motors M and M¹ may be allowed to coast to a dead-stop, and if the compartment doors 6 and 7 of cylinder 5 do not happen to stop in registering relation to the casing door aforementioned, such registration may be effected manually by engaging worm 13 with pinion or gear 14 and thereafter turning or rotating the worm by means of crank handle 15. In actual practice, however, I prefer to employ a manually operable brake 12 which may be utilized to minimize the time required for stopping of motor M, and to finally effect stopping thereof with the compartment doors properly registered with the casing door. If for any reason such registration is not effected by manipulation of brake 12, the worm and pinion means aforescribed may be utilized to effect final angular positioning of the cylinder 5. Moreover, the worm and pinion arrangement may be utilized to lock or positively hold the cylinder 5 in the desired position thereof during unloading and loading of the cylinder compartments.

What I claim as new and desire to secure by Letters Patent is:

1. In a control system of the character described, in combination, a pair of electric motors, common means operable to simultaneously connect said motors across a suitable source of energy supply, means comprising resistance to be initially included in circuit with said motors jointly, means responsive to given current conditions in the circuit of one of said motors to effect exclusion of said resistance and thereby tending to simultaneously increase the speeds of both of said motors, and means including additional resistance to be included in circuit with the other of said motors individually to provide for acceleration control of the latter upon exclusion of said first mentioned resistance.

2. In a control system of the character described, in combination, a pair of electric motors, common means operable to simultaneously connect said motors across a suitable source of energy supply, means comprising resistance to be initially included in circuit with said motors jointly, means responsive to given current conditions in the circuit of one of said motors to effect exclusion of said resistance and thereby tending to simultaneously increase the speeds of both of said motors, and means including additional resistance to be included in circuit with the other of said motors individually and to be excluded from said circuit in steps to provide for acceleration control of the latter upon exclusion of said first mentioned resistance.

tion control of the latter upon exclusion of said first mentioned resistance.

3. In a control system of the character described, in combination, a pair of electric motors, common means operable to simultaneously connect said motors across a suitable source of energy supply, means comprising a resistance element to be initially included in circuit with said motors jointly, means responsive to given current conditions in the circuit of one of said motors to effect exclusion of said resistance element and thereby tending to simultaneously increase the speeds of both of said motors, and means including additional resistance to be included in circuit with the other of said motors individually and to be excluded from said circuit in steps to provide for acceleration control of the latter upon exclusion of said first mentioned resistance element, said last mentioned means including means for automatically effecting periodic reversal of operation of said last mentioned motor.

4. In a control system of the character described, in combination, an electric motor to be connected across a suitable source of energy supply to provide for unidirectional operation thereof, a resistance element to be initially included in circuit with said motor to limit the value of energy supplied thereto, means operable automatically in response to given current conditions in said motor circuit to effect exclusion of said resistance element whereby said motor is accelerated, a second electric motor to be connected across said source of energy supply, reversing and accelerating control means for said second mentioned motor, said means including a drum arranged to be driven by said first mentioned motor, a plurality of resistance sections to be controlled by said drum, and associated means to likewise insure initial inclusion of said first mentioned resistance in circuit with said second mentioned motor.

5. In a control system of the character described, in combination, an electric motor to be connected across a suitable source of energy supply to provide for unidirectional operation thereof, a resistance element to be initially included in circuit with said motor to limit the value of energy supplied thereto, means operable automatically in response to given current conditions in said motor circuit to effect exclusion of said resistance element whereby said motor is accelerated, a second electric motor to be connected across said source of energy supply, reversing and accelerating control means for said second mentioned motor, said means including a drum arranged to be driven by said first mentioned motor, a plurality of resistance sections to be controlled by said drum, associated means to likewise insure initial inclusion of said first mentioned resistance in circuit with said second mentioned motor, and said drum and said resistance sections cooperating to effect acceleration control of said second mentioned motor independently of said first mentioned motor after exclusion of said first mentioned resistance.

6. The combination with a drying tumbler including a rotatable container, of an electric motor having a driving connection with said container, control means for said motor including a rotatable drum and a plurality of associated resistance sections, said drum being normally operable to sequentially provide reverse circuit connections for said motor and the same cooperating with said resistance sections to provide for acceleration of said motor, a fan adapted to supply a

flow of fluid to said container, a second electric motor having a driving connection with said fan, said second motor also having a driving connection with said drum, a normally open electromagnetically operable switch adapted when closed to complete a circuit for effecting unidirectional operation of said second motor, a normally open manually operable switch adapted upon closure thereof to effect energization and closure of said switch first mentioned, said second motor having a resistance element initially included in the circuit thereof, said first motor also having connections to insure initial inclusion of said resistance element in circuit therewith, means responsive to predetermined current conditions in the circuit of said second motor to effect exclusion of said resistance element whereby said second motor is accelerated, and said drum and said resistance sections acting under the last mentioned conditions to effect acceleration control of said first motor independently of said resistance element.

7. The combination with a drying tumbler comprising a rotatable container and a fan for supplying a flow of air to said container, of a relatively large unidirectionally operable electric motor having a driving connection with said fan, a relatively small reversible electric motor having a driving connection with said container, means for effecting periodic reversal and acceleration control of said relatively small motor, said means comprising a pilot drum and a plurality of resistance sections associated therewith, said relatively large motor having a driving connection with said drum, a starting resistance element to be included in the armature circuit of said relatively large motor, means for likewise initially including said resistance element in the armature circuit of said relatively small motor, a normally open electromagnetically operable switch adapted when closed to provide for substantially simultaneous completion of the armature circuits of both of said motors, a pair of push button switches respectively adapted to provide for energization and de-energization of said switch at will, and means responsive to given current conditions in the armature circuit of said relatively large motor to effect exclusion of said resistance element, whereupon said drum and associated resistance sections are adapted to function in the usual manner to effect periodic reversal and acceleration control of said relatively small motor.

8. The combination with a drying tumbler comprising a rotatable container and a fan for supplying a flow of air to said container, of a unidirectionally operable electric motor having a driving connection with said fan, a reversible electric motor having a driving connection with said container, a normally open electromagnetically operable switch adapted when closed to complete a circuit for said first mentioned motor, means including a resistance element to be initially included in circuit in series with the armature of said first mentioned motor, means including a unidirectionally operable drum and a plurality of resistance sections which cooperate to provide for periodic reversal and acceleration control of said second mentioned motor, said first mentioned motor having a driving connection with said drum, said drum and said resistance sections being so arranged as to insure initial inclusion of said first mentioned resistance in circuit in series with the armature of said second mentioned motor to provide for protection of the

latter during starting, means including a second normally open electromagnetically operable switch having an operating winding connected across the armature of said first mentioned motor, said winding being operable under given current conditions to effect closure of said switch where-

by said resistance element is short-circuited, and manually operable means to provide for energization and de-energization of said first mentioned electromagnetically operable switch at will.

RALPH G. LOCKETT.
